UNITED STATES PATENT OFFICE.

JOHN HERBERT KJELLSTROM, OF ROCKFORD, ILLINOIS, ASSIGNOR TO J. L. CLARK MANUFACTURING CO., OF ROCKFORD, ILLINOIS, A CORPORATION OF ILLINOIS.

METALLIC SPOOL.

Application filed January 20, 1927. Serial No. 162,250.

This invention pertains to metallic spools of the type generally employed in packaging adhesive tape and consisting generally of three members, namely, two end members or 5 heads and a cylindrical body.

Such spools are used largely by physicians and surgeons, and it is the practice to grasp the spool between the thumb and forefinger, placing one at each end of the main tubular 10 body of the spool. Held in such a manner, the spool may be turned so as to remove the material wound thereon.

Spools as heretofore manufactured have in many instances been objectionable in that the 15 construction preferred because of its simplicity, and hence most commonly employed in fastening the heads on the ends of the tubular body, leaves exposed sharp edges such as to tear or cut the fingers or gloves of 20 the user.

One object of this invention, therefore, is to provide a new and improved spool in which the objectionable cutting edges are concealed, and which at the same time may 25 be cheaply manufactured.

Another object is to provide a novel method of assembling my improved metallic spool.

Other objects and advantages will become apparent from the following disclosure and 30 the accompanying drawings, in which:

Figure 1 shows in elevation my improved form of spool.

Fig. 2 is an enlarged fragmentary view of one end of the completed spool in longitudinal section.

Fig. 3 is an enlarged fragmentary view in longitudinal section showing a spool which lacks one step of complete assembly, namely the stamping in place of the smooth guard ring which is shown above the end of the spool 10 in position for the stamping operation.

Fig. 4 is an enlarged fragmentary view in longitudinal section showing the elements of the spool after the final stamping operation.

In producing my improved spool, I employ 5 a construction common in the art and preferred because of its simplicity, with the addition of a very simple and yet effective means for concealing sharp cutting edges. 10 Thus my improved spool comprises a cylindrical body 5 formed from a flat piece of sheet metal, the two edges meeting at 6, and tending to form a narrow slot. The heads 7 are similarly formed and strengthened by forming annular beads 8 on the outer edge there-

of. Each disk or head has a central aperture through which the ends of cylinder 5 may project, and about the aperture a groove 9 is formed, the purpose of which will hereinafter appear.

The preferred construction employed to secure the heads 7 onto the opposite ends of the cylindrical body 5 consists in forming an annular outwardly projecting bead 10, spaced a short distance from the end of said cylinder, between which bead and an out-turned flange 11 formed on each end of the body, the head 7 is clamped.

It will be observed that this construction leaves exposed the sharp cutting edges of the 70 slot 6 and the flange 11. To protect the user against these cutting edges, I employ a simple U-shaped guard ring 12 made from a disk of sheet metal. The outer peripheral edge of this disk is drawn to form a depending flange 75 13, adapted to fit into the annular groove 9 in the head 7 so that its edge is unexposed; and the inner portion of the ring is drawn to form a similar depending flange 14 which may be of any desired length sufficient to 80 protect the hands of the user from the edges of the slot 6, and from its own edge.

In practice the several parts of my spool may be assembled as follows:

In one operation, the end of the cylinder 85 is inserted into the aperture in the head 7, and the end of said cylinder bent outwardly to form flange 11. Simultaneously the outwardly extending bead 10 on the body 5 is flattened against the inner side of the head 7. 90 The flattened bead 10 and the flange 11 will then form an outwardly facing annular groove in the tubular body 5, and into this groove will extend that annular portion of the head 7, between the annular groove 9 and 95 the central aperture. The head 7 is thus firmly held in place through contact with flange 11 on the outer side and bead 10 on the inner side.

In another operation, the guard ring 12, 100 having been previously formed, is inserted, the flange 13 being embedded in the annular groove 9 in the head 7, and the flange 14 extending into the cylinder 5. The guard ring 12 thus has a driving fit in the end of the 105 spool, and effectively conceals all the sharp edges of the flange 11 and the tubular body 5.

It will be apparent that the spool constructed as herein described is of extremely simple construction, the guard ring, while 110

serving to avoid the objections incident to prior spools does not add appreciably to the cost of the spool. I do not, however, claim as my invention the guard ring apart from its 5 association with the spool head, substantially as set forth, since this guard ring in its broader aspects is the invention of Wallace C. Mills and forms the subject matter of a copending application, Serial No. 281,011, 10 filed May 28, 1928.

I claim as my invention:

1. The combination with a metallic spool comprising a main tubular body formed from a sheet of metal, and having an annular bead 15 and an annular flange adjacent the end thereof, the abutting edges of which form a slot, and an apertured head on the end thereof secured between said bead and said flange, said head having a narrow annular groove open-

ing endwise of said spool, of a guard ring 20 having two spaced flanges, one fitting snugly into said groove and the other being adapted to fit snugly into said tubular body so as to cover the end of said slot.

2. A metallic spool comprising, in combination, a main tubular body bent from a sheet the terminal ends of which form a narrow slot, a centrally apertured head secured to one end of said body, said head having a narrow annular groove formed therein, 25 and a guard ring of substantially U-shaped cross section extending from within said tubular body over the end thereof and into said groove.

In testimony whereof, I have hereunto 30 affixed my signature.

JOHN HERBERT KJELLSTROM.
